[57] CLAIM

The ornamental design for a chair, as shown and described.

DESCRIPTION

FIG. 1 is a perspective view of a chair showing my new design;

FIG. 2 is a front elevational view thereof;

FIG. 3 is a side elevational view thereof, the opposite side being a mirror image thereof;

FIG. 4 is a rear elevational view thereof;

FIG. 5 is a top plan view thereof;

FIG. 6 is a bottom plan view thereof;

FIG. 7 is a perspective view of a second embodiment of a chair showing my new design;

FIG. 8 is a front elevational view of the second embodiment thereof;

FIG. 9 is a side elevational view of the second embodiment thereof, the opposite side being a mirror image thereof;

FIG. 10 is a rear elevational view of the second embodiment thereof; and,

FIG. 11 is a top plan view of the second embodiment thereof, the bottom plan view of which is identical to the bottom plan view of the first embodiment illustrated in FIG. 6.
